UNITED STATES PATENT OFFICE.

WILLIAM N. WHITELEY, OF SPRINGFIELD, OHIO.

KNOTTING DEVICE FOR GRAIN-BINDERS.

SPECIFICATION forming part of Letters Patent No. 372,506, dated November 1, 1887.

Application filed April 30, 1887. Serial No. 236,702. (No model.)

To all whom it may concern:

Be it known that I, WILLIAM N. WHITELEY, a citizen of the United States, residing at Springfield, in the county of Clark and State of Ohio, have invented certain new and useful Improvements in the Knotting Devices of Grain-Binders—namely, an Automatic Cord-Supporting Finger therefor—of which the following is such a full, clear, and exact description as will enable any person skilled in the art to construct and use the same, reference being had to the accompanying drawings, forming a part of this specification.

My invention relates to the knotting devices of that type of grain-binders generally known as the "Appleby Binder," which is shown and described in Letters Patent No. 212,420, granted to J. F. Appleby, February 18, 1879, (and since improved by various inventions,) and is in the nature of an improvement on the mechanism for supporting the binding-cord previous to forming the knot.

My invention consists in providing a novel device for operating a cord-supporting finger such as is described in my application for Letters Patent filed September 16, 1886, the serial number whereof is 213,682, the said cord-supporting finger being adapted "to support the cord above and in advance of the bill-hook during the interval in which the usual knot-stripper and cord guide has moved out of its initial position when the binding-cord is severed after forming the previous knot."

In the drawings, Figure 1 is a perspective view of the essential parts of a knotter, showing the cord-finger in the act of supporting the cord. Fig. 2 is a similar view showing the cord-finger thrown back out of the way and the cord in place guided by the usual cord-guide and knot-stripper. Fig. 3 is a face view of the cam for throwing the cord-finger back to the position shown in Fig. 2. Fig. 4 is an edge view of said cam, and Fig. 5 is an end elevation of the device for holding the cord-finger in place when not acted upon by the operative parts.

Similar letters refer to like parts in the several views.

A is the knotter-frame, B is the breast-plate, C the tyer-wheel, D the bill-hook, E the tucker-finger, F the cord-guide and knot-stripper, G the cord-holder disk, P is the cord-holder shoe,

c is the tyer-wheel shaft, all constructed and arranged as usual.

Pivoted upon a stud, h, is the cord supporting finger H. Outside of the finger H and upon the stud h is a spring, d, secured thereon by the washer i and pin j, the object of which is that the pressure of the spring d against the finger H may act as a check, preventing it from moving out of its place except when acted upon by the parts designed to operate it.

Upon the tyer-wheel shaft c is fixed the cam K, which acts upon the sliding rod L, one end of which slides through the perforated ear a, 65 formed on the knotter-frame A, and the other end is bent to a right angle and is pivoted in the upper end of the cord-finger H above the stud h, on which it is pivoted. The function of these operative parts is to throw back the cord-finger to the position shown in Fig. 2, the end of the rod L resting in the cam-track k of the cam K when in the position shown in Fig. 1, and upon the plain surface of the cam when in the position shown in Fig. 2. Enlarged views 75 of the cam K are shown in Figs. 3 and 4.

In the second or supplemental part, f, of the stripper F is a pin, m, which projects through a slot formed in the cord-finger H at a point below the stud h, on which it is pivoted. The 80 vibrating motion of the part f thus throws the cord-finger forward to the position shown in Fig. 1, the elongation of the slot allowing the cord-finger H to be held in place by the spring d, although the pin m may have moved back. 85

The operation of my device is as follows, viz: The knotter being in the position shown in Fig. 1, and the needle-arm (not shown) retiring after a sheaf is bound, leaves the end of the cord in the cord-holder disk G and 90 cord-holder shoe P, (shown, principally, by dotted lines,) and lays the cord across the cord-finger H, as shown in Fig. 1. The tyer-wheel C and cam K now rotate in direction of the arrows, the incline n of the cam-track k comes 95 in contact with the end of the rod L, forcing it toward the tyer-wheel C, and throwing the lower end of the cord-finger back, as shown in Fig. 2, allowing the cord x to drop off the end of the cord-finger and into the usual cord-notch of the stripper F, as seen in Fig. 2, the stripper having been advanced for that purpose and a little in advance of the movement of the cord-finger by the usual cam-track, g,

in the tyer-wheel acting on the friction-roller *p*, pivoted on the extended end of the part *f* of the stripper *F* in the usual manner. The incline *n* of the cam-track *k* of the cam *K* having passed the end of the rod *L*, the rod remains stationary, as does the stripper *F*, until the tucker-finger *E*, operated by the cam-track *r* of the tyer-wheel *G*, has acted on the cord and tucked it under the bill-hook *D* and the latter has rotated and tied the knot. The cam-track *q* of the tyer-wheel *C* now acts on the roller *p* on the extended end of the part *f* of the stripper *F*, throwing it back to the position shown in Fig. 1 and stripping the knot from the bill-hook *D*, by which movement the pin *m* in the part *f* of the stripper *F* acts upon the cord-finger *H*, throwing it forward to the position shown in Fig. 1 in time to receive and support the cord *x* as the needle-arm (not shown) retires preparatory to the formation of another gavel.

The foregoing operations are repeated at the binding of each sheaf.

Having now described my invention and

shown its construction, operation, and use, 25 what I claim, and desire to secure by Letters Patent, is—

The combination, in the knotting device of a grain-binding machine, of a cord-supporting finger adapted to support the cord above and 30 in front of the bill-hook, a pin fixed in the stripper for throwing said cord-finger forward into a position to receive the cord, a sliding rod pivoted to said cord-finger and adapted to be acted on by a cam to force it endwise 35 and thus throw the cord-finger out of the way after having performed its function, and a suitable cam fixed to the tyer-wheel shaft for operating said sliding rod, substantially as and for the purposes shown and described. 40

In testimony whereof I have signed this specification, in the presence of two witnesses, this 18th day of April, A. D. 1887.

WILLIAM N. WHITELEY.
